UNITED STATES PATENT OFFICE.

HERBERT E. ENSLIN, OF BEVERLY, MASSACHUSETTS, ASSIGNOR TO UNITED SHOE MACHINERY CORPORATION, OF PATERSON, NEW JERSEY, A CORPORATION OF NEW JERSEY.

LACING MACHINE.

Application filed July 19, 1920. Serial No. 397,403.

To all whom it may concern:

Be it known that I, HERBERT E. ENSLIN, a citizen of the United States, residing at Beverly, in the county of Essex and State 5 of Massachusetts, have invented certain new and useful Improvements in Lacing Machines; and I do hereby declare the following to be a full, clear, and exact description of the invention such as will enable others 10 skilled in the art to which it appertains to make and use the same.

The invention relates to machines for lacing shoe uppers, in which one or more spindles are arranged to pass a series of 15 loops of lacing cord through the eyelet holes of an upper.

The object of the invention is to provide for the ready and convenient removal and insertion of the looper spindles and for the 20 accurate and uniform positioning of the spindles in their carriers. To this end each spindle is provided with a radial projection which is confined between the end of the carrier and a retainer, and thus determines 25 and fixes the endwise position of the spindle. The retainer is preferably mounted so that it may be moved out of its retaining position in front of the projection and thus permit the removal or insertion of the spindle. The circumferential position of the 30 spindle may be, and preferably is, fixed and determined by a lip on the end of the spindle carrier arranged to register with and engage a flattened or eccentric surface on 35 the spindle.

The invention will be readily understood from an inspection of the accompanying drawings and the following detailed description of the mechanism illustrated 40 therein.

In the drawings Fig. 1 is a front elevation showing the support in which the looper spindles and cooperating looper fingers are mounted, Fig. 2 is a side elevation 45 of the same, and Fig. 3 is a sectional detail on an enlarged scale, the section being taken on a line passing vertically through one of the looper spindles.

In the drawings the invention is shown as 50 embodied in an upper lacing machine having substantially the construction and mode of operation of the machine shown and described in Patents No. 1,030,547 and

1,030,573, June 25, 1912. In this machine a series of loops of lacing cord is held by 55 a series of looper spindles 2, and a cooperating series of looper fingers 4, in position to be passed through the eyelet holes of an upper. The spindles are mounted in spindle carriers 6, which are in turn mounted to oscillate in blocks 8, laterally adjustable in a vertically movable support 10. In the construction shown each spindle carrier is provided with a socket for receiving the inner end of the corresponding spindle. 60 The spindle is provided with a radially projecting collar or flange 12 arranged to engage the outer end of the carrier and thus determine the lengthwise position of the spindle. The flange is slabbed off on the 65 lower side to form a flat eccentric surface 14, which is arranged to be engaged by a lip 16 projecting from the end of the carrier, and acting to determine the circumferential position of the spindle and to 70 firmly hold it from turning within its socket. The spindles are firmly held in position against lengthwise movement within their sockets by a retainer bar 18, arranged to engage the front faces of the flanges 12, 75 and to confine the flanges between the bar and the ends of the carriers 6. In order that the bar may be conveniently and quickly moved into and out of active position when one or more of the spindles is to be removed, 80 inserted or changed, it is provided with rearwardly projecting arms 20 which are connected with the support 10 by pivots 22. The bar is held normally in active position by springs 24, which yield to permit upward movement of the bar when it is to be 85 removed from active position.

While it is preferred to employ the specific construction and arrangement of parts shown and described in applying the invention to the machine of the patents above referred to it will be understood that this construction and arrangement is not essential to the broader features of the invention and may be varied or modified as found desirable or best suited to the construction of the machine in which it is to be embodied.

What is claimed is:

1. A lacing machine having, in combination, a spindle carrier provided with a 105 socket, a looper spindle fitting therein pro-

- vided with a radial projection for engaging the end of the carrier, and a retainer for engaging the outer face of the projection.
2. A lacing machine having, in combination, a spindle carrier provided with a socket, a looper spindle fitting therein provided with a radial projection for positioning it lengthwise, and a retainer movable into and out of position in front of the projection.
3. A lacing machine having, in combination, a spindle carrier provided with a socket, a looper spindle fitted therein provided with a radial projection for determining the lengthwise position of the spindle, a retainer movable into and out of position in front of the projection, and means for fixing the circumferential position of the spindle.
4. A lacing machine having, in combination, a spindle carrier provided with a socket, a looper spindle provided with a flange having an eccentric surface, a lip on the carrier for engaging the eccentric surface to determine the circumferential position of the spindle in the carrier, and a retainer for engaging the outer face of the flange to determine the lengthwise position of the spindle in the carrier.
5. A lacing machine having, in combination, a spindle carrier provided with a socket and having a lip at its outer end, a looper spindle fitting therein provided with a flange having an eccentric surface for engaging the lip, and a retainer movable into and out of position in front of the flange. 35
6. A lacing machine having, in combination, a series of spindle carriers, each provided with a socket, looper spindles fitted therein, each provided with a radial projection, and a retainer movable into and out 40 of position in front of the series of projections.
7. A lacing machine having, in combination, a series of spindle carriers each provided with a socket, a support in which the 45 carriers are laterally adjustable, looper spindles fitting within the sockets in the carriers, each provided with a radial projection, and a retainer bar mounted on the support for movement into and out of position 50 in front of the radial projections.
8. A lacing machine having, in combination, a series of spindle carriers, each provided with a socket, a support in which the carriers are laterally adjustable, looper 55 spindles fitting within the sockets in the carriers, and each provided with a flange having an eccentric surface therein, lips on the carriers registering with the eccentric surfaces on the flanges, and a retainer bar mounted on the support for movement into and out of position 60 in front of the flanges.

HERBERT E. ENSLIN.
